UNITED STATES PATENT OFFICE.

FRANK S. CAPELLO, OF SCHENECTADY, NEW YORK, ASSIGNOR TO GENERAL ELECTRIC COMPANY, A CORPORATION OF NEW YORK.

SNAP-SWITCH.

No. 905,792.

Specification of Letters Patent.

Patented Dec. 1, 1908.

Application filed October 8, 1907. Serial No. 396,393.

To all whom it may concern:

Be it known that I, FRANK S. CAPELLO, a citizen of the United States, residing at Schenectady, county of Schenectady, State of New York, have invented certain new and useful Improvements in Snap-Switches, of which the following is a specification.

This invention relates to rotary electric switches of the quick-break type, in which the rotatable spindle is connected with the rotary switch-blade by a helical spring which is tensioned by the turning of the spindle; the blade being locked from moving until a catch-plate movable thereon has been disengaged from a fixed stop by the rotation of the spindle through a predetermined arc. In many switches of this type the catch-plate reciprocates in guides on the switch-blade and is moved by a crank-pin, or other actuator, on the spindle, engaging in a suitably shaped slot in said catch-plate. A longer slot is made in the catch-plate to permit the spindle to pass through it, and it sometimes happens that the actuating pin or arm slips out of its proper notch into the long slot and becomes jammed therein, so that the switch is rendered inoperative and is liable to be broken.

The object of my invention is to prevent this trouble, and I accomplish this result by making the pin radially movable in or on the spindle, and so shaping the slot in the catch-plate that the pin is held at all times in its proper position without any possibility of accidental displacement.

The accompanying drawing represents the preferred embodiment of my invention, Figure 1 being a top plan view of a double-pole switch with the spindle in cross section; Fig. 2 a vertical section of the complete switch; Figs. 3, 4 and 5 diagrams showing the operation of my improved actuator; Figs. 6 and 7 perspective views, respectively, of the catch-plate and actuator.

The switch has the customary base 1 made of insulating material and supporting four posts 2 3 to which are secured the contact clips 4 5. The spindle 6 is centrally located with reference to said posts 2 3 and is journaled preferably in a stationary plate 7 fastened to the base by screws 8. This plate has on its periphery four equidistant ratchet teeth 9 serving as stops to arrest the rotation of the switch blades or pole pieces 10 11. The latter are secured to a barrel of insula-

tion mounted on the spindle and freely rotatable thereon. The spindle is yieldingly connected to the barrel by a helical spring 12 surrounding the spindle and attached thereto at its upper end. The lower end of the spring is hooked around one of a number of studs 13 projecting from the top of the barrel and affording a convenient means for adjusting the tension of the spring by changing it from stud to stud. The two switch-blades are insulated from each other, and the lower one has downwardly turned parallel ledges or flanges 14 serving as guides for the sliding catch-plate 15. At one end of the catch-plate is a downwardly projecting lug 16 adapted to engage with the ratchet teeth 9 on the stop-plate 7. The catch-plate is slotted longitudinally to enable it to slide transverse to the spindle which passes through it. In the plane of this plate the spindle carries a transversely slidable actuator engaging with said slot. The preferred construction is that shown in the drawing in which the actuator has a square shank 17 fitted to slide in a round hole in the spindle. A square shank is much less expensive to make than a round one, as it can be punched in a die press. The head 18 of the actuator is preferably a circular disk and it engages in a semi-circular notch 19 in one side of the slot 20 in the catch-plate. The side 21 of the slot opposite the notch is concentric therewith, being struck on a radius equal to the length of the actuator, which is such that the end of the shank always projects beyond the spindle. The result of this construction is that when the catch-plate is at the end of its stroke, the projecting end of the shank prevents the spindle from rotating in a direction which would disengage the disk from its notch. Moreover, when the spindle is turned the other way, to actuate the catch-plate, the actuator is permitted to slide back through the spindle, as shown in Fig. 4, so that its effective radius is shortened and its purchase on the catch-plate is correspondingly increased as the tension of the spring increases, and the consequent friction of the lug on the ratchet-tooth becomes greater. As the slide nears the end of its stroke, the circular side 21 of the slot pushes the actuator outwardly so that the head 18 thereof is kept in close engagement with its notch 19. The same is true when the lug 16 slips off the tooth 9 of the stop-plate and the parts snap back to

110

their original positions, as shown in Figs. 3 and 5, the shank abutting against the end of the slot 20 and locking the spindle against backward movement.

5. The operation of this type of snap action is so well known to those skilled in the art that it is not deemed necessary to go into it at length. It is also evident that the invention is applicable to single-pole switches as well as 10 to double-pole ones.

What I claim as new and desire to secure by Letters Patent of the United States, is,—

1. In a snap switch, the combination with a spindle, of a catch-plate having a 15 slot, and an actuator engaging with said slot and adapted to slide transversely of said spindle.

2. In a snap switch, the combination with a spindle, of an actuator adapted to 20 slide transversely thereof, and a catch-plate having a slot containing a notch on one side with which one end of said actuator engages, the opposite side of said slot being concentric with said notch and engaging the other 25 end of said actuator.

3. In a snap switch, the combination with a spindle having a transverse hole, of

an actuator having a square shank fitting said hole and a circular head, and a catch-plate having a slot containing a semi-circular notch to engage said head. 30

4. In a snap switch, the combination with a spindle having a transverse hole, of an actuator adapted to slide therein and having a shank long enough to project 35 beyond said spindle at all times, and a catch-plate having a slot always in engagement with both ends of said shank.

5. A base having contacts, a catch secured thereto, a trip plate having a trip coöperating with said catch and provided with a coupler opening having opposite edges formed on the arcs of concentric circles, means for rotating the trip, a switch bar having contacts and operatively connected with the 45 trip, primary actuating means, and a coupler fitting said coupler opening and loosely engaging with said primary actuating means.

In witness whereof, I have hereunto set my hand this 4th day of October, 1907.

FRANK S. CAPELLO.
